Primary Examiner — W. A. Teddy Falloway*Assistant Examiner* — Katrina N Gonzalez(74) *Attorney, Agent, or Firm* — Nelson Mullins Riley & Scarborough LLP(57) **CLAIM**

The ornamental design for a feeder spoon, substantially as shown and described.

DESCRIPTION

FIG. 1 is a front, left perspective view of a feeder spoon, in accordance with my design;

FIG. 2 is a front, right perspective view thereof;

FIG. 3 is a top perspective view thereof;

FIG. 4 is a top plan view thereof;

FIG. 5 is a bottom plan view thereof;

FIG. 6 is a right elevation view thereof, the left elevation view being a mirror image;

FIG. 7 is a front elevation view thereof; and,

FIG. 8 is a back elevation view thereof.

The broken lines illustrate portions of the feeder spoon that form no part of the claimed design.

1 Claim, 6 Drawing Sheets(56)
